Patented Dec. 28, 1926.

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 12, 1924, Serial No. 719,692. Renewed August 5, 1928.

My invention relates to mining apparatus.

An object of my invention is to provide an improved chain propelled mining apparatus and more particularly an improved chain stripping mechanism associated with the feeding mechanism of such an apparatus. Another object of my invention is to provide a chain propelled mining machine having an improved chain stripper mechanism whereby the feed chain, which cooperates with a feed sprocket during the operation of the machine, may be diverted from the feed sprocket, thereby preventing jamming and consequently breakage of the chain and its cooperating parts caused by the chain sticking to the sprocket. Still another object of my invention is to provide an improved reversible pivoted chain stripper mechanism whereby the feed chain may be diverted from the feed sprocket on either side thereof. A still further object of my invention is to provide a chain propelled mining machine having improved chain stripper mechanism which is held in its operative position by means of the feed chain. These and other objects and advantages of my invention will, however, hereinafter more fully appear.

In the accompanying drawings I have shown for purposes of illustration one form 30 which my invention may assume in practice.

In these drawings,

Fig. 1 is a plan view of the mining machine in which my improved mechanism is incorporated, the cutter bar being shown in 35 under-cutting position.

Fig. 2 is an end elevation of the mining machine, shown in Fig. 1, with my improved chain stripper mechanism shown in operative position.

Fig. 3 is an end elevation of the mining machine, shown in Fig. 1, when being 40 utilized as an over-cutter.

Fig. 4 is a transverse horizontal detail sectional view taken substantially on line 45 4-4 of Fig. 2.

Fig. 5 is a detail side elevation of my improved chain stripper mechanism.

In this illustrative form of my invention I have shown a mining machine of a self-propelled longwall type adapted to slide on 50 its own bottom and having an elongated frame 1 presenting parallel plane surfaces 2 and 3 upon which the mining machine is selectively adapted to slide during cutting, 55 that is, when the machine is being used as

an under-cutter or an over-cutter. The frame 1 carries at its rear end a pivoted cutter bar 4 provided with an endless cutter bit carrying cutter chain 5 which is adapted to be circulated about the cutter bar in a well known manner, the mining machine also, herein, being adapted to move longitudinally along the face of the material to be cut relative to a flexible feeding member, herein a feed chain 6, adapted to cooperate with a feed sprocket 8 rotatable on a longitudinally extending horizontal axis on the front end of the machine frame. A plurality of guiding sprockets or sheaves 9, 10, 11, 12, 13, 14, 15, and 16 are disposed on vertical axes adjacent the feed sprocket 8 and at the sides of the machine, with which the feed chain 6 is selectively adapted to cooperate during the various operations of the machine. The feed sprocket 8 is grooved, as at 17, and is provided with sprocket teeth 18 with which the links of the feed chain cooperate.

In my improved construction it will be noted that the feed sprocket is journaled on a longitudinally extending horizontal shaft 19 and is provided at its outer end with a cup-shaped retaining member 20 held in position by means of a suitable bolt 21 secured to the shaft 19, thereby preventing displacement of the feed sprocket from the shaft. The retaining member 20 is provided with a radially extending flange 22 which retains an annular hub 23 in position, the hub being journaled, as at 24, on the retaining member 20. This hub is formed on and carries a chain stripper mechanism, generally designated 25, of improved form which is provided at its upper and lower edges with grooved guiding surfaces 26 and 27 which are adapted to engage the feed chain 6 and, in turn, with an inwardly projecting member or finger 28 which projects into the circular groove 17 formed in the feed sprocket 8.

In the use of my improved mechanism as shown in Figs. 1, 2, 4, and 5 it will be noted that the advance portion of the feed chain 6 is secured to a suitable extraneous abutment or jack (not shown) and is extended along the working face around the lower inner guide sheave 16 and transversely and rearwardly around the guide sheave 10, the slack or receding portion of the chain passing transversely from the machine. The

grooved portion 27 of the chain stripper rests on the top surface of the taut advance portion of the feed chain and is held thereby in its operative position during the operation 5 of the feed sprocket. The feed sprocket 8 is then rotated in a counter-clockwise direction at a slow speed causing the fixed or advance portion of the feed chain to be acted on, consequently causing the machine to 10 move forwardly relative to the chain along the face. The feed chain comes on to the feed sprocket 8 at a point indicated at 29, and is required to leave this feed sprocket, by means of the stripper, at a point indicated at 30. The load or stress on the feed chain during feeding causes the latter to cling or stick to the feed sprocket, and in the absence of the chain stripper frequently causes the chain to pile up, jam, or to be 15 wound on the sprocket, interrupting the feed and consequently resulting in a broken feed chain or damaging other cooperating feeding parts. To prevent this the chain stripper is provided. The inwardly projecting finger 28 of the chain stripper which extends into the groove 17 formed in the sprocket, pushes the links of the free or slack receding end of the feed chain from the sprocket, thereby preventing jamming 20 and breakage of the chain. When the machine is turned over in its over-cutting position, as indicated in Fig. 3, with the surface 2 of the mining machine disposed on the mine bottom, the advance portion of the feed chain passes from the jack along the face to the lower inner guide sheave 9 transversely of the machine and forwardly 25 around the guide sheave 11 beneath and upwardly around the feed sprocket 8, the slack chain then passing transversely of the machine. When the machine is in this position the chain stripper mechanism 25 is swung around the bearing 24 on the retaining member 20 to the opposite side of the feed 30 sprocket, the lower grooved portion 27 still riding on the taut feed chain at this time. Obviously if a reversible driving motor were utilized, as is common in this art, the chain stripper 25 will act in the manner similar 35 to that described above with the exception that the chain 6 will be diverted from the sprocket 8 from the opposite surface thereof.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, feeding mechanism including a rotatable feed sprocket

and a cooperating feed chain, and means held in operative position by said chain for diverting the same from said sprocket.

2. In a mining machine, feeding mechanism including a rotatable feed sprocket 70 and a cooperating feed chain, and means held in a plurality of operative positions by said chain for diverting said chain from said sprocket.

3. In a mining machine, feeding mechanism including a rotatable feed sprocket 75 and a cooperating feed chain, and means pivoted on an axis coaxial with the axis of said sprocket for diverting said feed chain from said sprocket. 80

4. In a mining machine, feeding mechanism including a rotatable feed sprocket and a cooperating feed chain, and a pivoted stripper member held in operative position by said chain for diverting said chain from 85 said sprocket.

5. In a mining machine, feeding mechanism including a rotatable feed sprocket and a cooperating feed chain, and a stripper member provided with a chain engaging 90 finger pivoted on an axis coaxial with the axis of said sprocket. 95

6. In a mining machine, feeding mechanism including a rotatable feed sprocket and a cooperating feed chain, and a stripper member provided with a chain engaging finger held in operative position by said chain for diverting said chain from said 100 sprocket.

7. In a mining machine, feeding mechanism including a rotatable feed sprocket and a cooperating feed chain, and a pivoted stripper member provided with a member extending into the path of said chain for diverting said chain from said sprocket from either side thereof. 105

8. In a mining machine, feeding mechanism including a rotatable grooved feed sprocket and a cooperating feed chain, and means pivoted on an axis coaxial with the axis of said feed sprocket and extending into said groove for diverting said chain from said sprocket. 110

9. In a mining machine, feeding mechanism including a reversely rotatable grooved feed sprocket and a cooperating feed chain, and a pivoted stripper member provided with a finger extending into the path of said chain and into said groove for diverting said chain from said sprocket irrespective of the direction of rotation of the latter. 115

10. In a mining machine, feeding mechanism including a rotatable feed sprocket and a cooperating feed chain, and means adapted to be engaged by the advance and receding portions of said feed chain for diverting said chain from said sprocket. 125

11. In a mining machine, feeding mechanism including a rotatable feed sprocket 130 and a cooperating feed chain, and means

- pivoted on an axis coaxial with the axis of said feed sprocket provided with spaced chain engaging portions, one of which is adapted to divert, said chain from said sprocket.
12. In a mining machine, feeding mechanism including a rotatable feed sprocket and a cooperating feed chain, and means pivoted on an axis coaxial with the axis of said feed sprocket and adapted to be swung to opposite sides of said sprocket for diverting said chain from said sprocket.
13. In a mining machine, feeding mechanism including a rotatable feed sprocket and a cooperating feed chain, guiding sheaves for said chain, about which the latter may be variously reeved relative to
14. In a mining machine, feeding mechanism including a rotatable feed sprocket and a cooperating feed chain, and a pivoted stripper member held in operative position by said chain provided with a member extending into the path of said chain for diverting the latter from said sprocket irrespective of the direction of movement of the latter.
